CLOSURE OPERATOR

Albert J. Poteet, Lakeland, Fla.

Application June 2, 1938, Serial No. 211,456

2 Claims. (Cl. 268—119)

This invention relates to an improved closure operator particularly adapted for opening and closing and retaining casement windows in adjusted positions.

5 It is a particular object of this invention to provide an operator for swinging closures, particularly casement or French windows, having means manually actuated from within to swing the closure through an arc of substantially one hundred and eighty degrees, and to retain the closure at any desired point throughout its arc of movement.

More particularly, it is an object of this invention to provide an operator including a manually actuated worm and gear to actuate a link and lever to swing a vertically hinged closure from its closed position through an arc of substantially one hundred and eighty degrees or until the closure is parallel to or in engagement with the outer side of the building of which it forms a part.

20 The advantage of this invention resides in the fact that vertically hinged closures such as casement windows may be actuated from within and swung to a fully opened position substantially parallel to the outer side of the building or wall to which it is connected so that the window when it is in open position will not form a baffle to divert air currents from the window opening.

Other objects and advantages of the invention will hereinafter become more fully apparent from the following description of the drawings which illustrate a preferred form of the invention, and wherein:

Figure 1 is a fragmentary side elevational view 35 looking toward the inner side of the lower hinged corner of a casement window to which the invention is attached.

Figure 2 is a horizontal sectional view taken on the line 2—2 of Figure 1.

40 Figure 3 is a vertical sectional view taken on the line 3—3 of Figure 2.

Figure 4 is a longitudinal vertical sectional view taken on the line 4—4 of Figure 2, and

45 Figures 5 and 6 are cross sectional views taken on the lines 5—5 and 6—6, respectively, of Figure 3.

Referring more particularly to the drawings wherein like reference characters designate like or corresponding parts throughout the different views, 10 designates generally a window opening of a building 11, said opening being provided with a conventional window frame 12 including a sill 13, and a casement window 14 vertically hinged at 15 to form a closure for the window opening 10. These parts are of conventional construc-

tion and are shown merely to illustrate the invention which will hereinafter be described.

A base plate 16 is secured at its four corners by fastenings 17 to the upper face of the sill 13, adjacent the hinged edge of the window 14. Plate 16 adjacent one of its ends, is provided with upwardly extending spaced ears 18 provided with openings 19, and a groove 20, in the upper face of plate 16 between ears 18 which is arcuately shaped in cross section, as best seen in Figure 5. 10

A worm 21 is positioned between ears 18 and is provided with a reduced shank 22 at one end adapted to be journaled in the opening 19 of the ear 18, which is adjacent to the window 14. Worm 21 at its opposite end is provided with a 15 recess 23 to receive one end of a shaft 24, which is journaled in the opening 19 of the other ear 18. The opposite end of shaft 24 fits into one end of a sleeve 25, and the pins 26 key shaft 24 to worm 21 and sleeve 25. Sleeve 25 is positioned 20 between the outer side of the last mentioned ear 18 and a bearing member 27 which is secured by the fastenings 28 to sill 13, in spaced relationship to plate 16. Bearing 21 is provided with an opening 29 which aligns with the openings 19 of ears 25 18 and with the bore 30 of sleeve 25, into one end of which the shaft 24 fits.

A crank 31 is provided with a stem 32 having a groove 33 extending from a point adjacent to, through its free end. Stem 32, as best seen in Figure 3, is journaled in the opening 29 of bearing 21 and has its free end extending into the bore 30 of sleeve 25, to be keyed thereto by the set screws 34 having the tapering ends 35 to fit the converging sides of the slot 33. Extending 35 upwardly through plate 16, adjacent its opposite end, is a headed pivot post 36 on which a gear sector 37 is rotatably mounted. An annular groove 38 is formed in the upper face of the plate 16 around the post 36 in which are mounted a 40 plurality of ball bearings 39 on which gear sector 37 is adapted to be supported and by means of which it is enabled to turn freely on post 36. Gear sector 37 is substantially a circular member having a series of teeth 40, cut in its edge and 45 extending through an arc of slightly more than one hundred and eighty degrees. An arm or lever 41, is formed integral with gear sector 37 and projects outwardly therefrom between the opposite ends of the series of teeth 40, and has a link 42 pivotally connected at 43 to its free end. Link 42 is pivotally connected at one of its ends at 43, and at its opposite end to a bracket 44 secured to the casement window 14 preferably on its bottom rail. 50 55

As best seen in Figure 2, arm 41 is positioned substantially parallel to the window 14, when the latter is in its closed position, and the link 42 is disposed at acute angles to arm 41 and window 14 in this position. The thread 45 of worm 21 which meshes with the teeth 40, and which is accommodated by the groove 20, will swing arm 41 toward window 14, when crank 31 is turned in a counterclockwise direction. The length of link 42 is less than that of lever 41, so that by turning crank 31 in a counterclockwise direction to move the gear sector 37 throughout the range of its teeth 40, window 14 may be swung through an arc of substantially one hundred and eighty degrees, or until it is parallel to the outer wall of the building 11 so that the window opening 10 may be fully exposed. If desired, the operation of gear sector 37 may be stopped at any point throughout its range of movement to retain the window 14 in a partially open position, such as indicated in dotted lines in Figure 2. Crank 31 is turned in an opposite direction, or clockwise to move the window 14 to a closed position.

While the operator has been described in combination with a casement window, for which it is particularly adapted, it is obviously equally well adapted for use with any other type of horizontally or vertically hinged closures, and the particular construction and arrangement of the parts forming the invention may obviously be modified and changed without departing from the underlying principle thereof, and the right is deserved to make such variations and changes as do not depart from the spirit and scope of the

invention as hereinafter defined by the appended claims.

I claim as my invention:

1. In a casement window operator, a base plate provided with an annular groove in its upper face forming a race for a plurality of ball bearings, spaced apertured ears extending upwardly from said base, a worm positioned between said ears and journaled therein, operating means for said worm comprising a shaft having a crank secured to its free end, a gear rotatably mounted on said ball bearings and having its teeth in engagement with said worm, a lever secured to said gear and projecting outwardly therefrom, and a link connecting the free end of said lever and a casement window, said link being disposed at an acute angle to the lever when the window is in a closed position and being of a length less than that of the lever to cause the window to be swung to a fully open position when said operator is actuated by the crank.

2. In an operator for swinging closures, a base plate having an annular groove forming a race for a plurality of ball bearings, a horizontally disposed actuator comprising a rotatably mounted worm, operating means for said worm, a gear sector having its teeth in engagement with the worm and rotatably mounted on said ball bearings, a lever connected to said gear sector and projecting outwardly therefrom, and a link pivotally connected at one end to the free end of the lever and adapted to be pivotally connected at its opposite end to a swinging closure.

ALBERT J. POTEET. 35
